UNITED STATES PATENT OFFICE

ERNEST HALL, OF FAIRFAX, ALABAMA

JACQUARD TYPE LOOM

Application filed January 6, 1930. Serial No. 418,924.

This invention relates to Jacquard type looms and has particular reference to jacquard mechanism and controlling means therefor.

- 5 In weaving terry towels and similar fabrics requiring jacquard mechanism including, for example, rugs and carpets, which fabrics have an intermediate and relatively long plain body portion of similar weave and 10 figured end portions or borders, it has heretofore been necessary to employ a card for each pick of the long body portion as well as cards for each pick of the end border patterns, these body cards numbering in the 15 thousands and involving a high cost in material, pattern punching labor and equipment and in stitching, as well as requiring accessories for handling the large number of cards in weaving. In terry towels of large size 20 (but relatively small compared to rugs and carpets) and having plain intermediate body portions and figured end borders, as many as forty eight hundred cards have heretofore been required.
- 25 Three picks are ordinarily required for the terry type weave unit and these, multiplied up to a thousand and possibly more, will indicate the number of cards heretofore required for the body pattern of large size 30 terry towels. With long rugs and carpets having plain intermediate body portions and figured end borders, the number required is proportionately increased.

By my invention, I eliminate the thousand 35 or thousands of cards required to repeat the intermediate body pattern weave unit and restrict the number used to a single set representing those necessary to form one complete weaving unit of the particular type 40 used in the body pattern which in the usual terry weave requiring three picks will be three cards instead of a thousand or more and provide means for automatically placing 45 in operation the border pattern cards at the end of the body pattern weaving. The instrumentalities for effecting this result are adaptable to different lengths of body weave and pattern or type and to different lengths 50 of border patterns so that the invention is applicable to all Jacquard type looms when

used to weave a repeated plain body or intermediate portion of fabric.

It may be here stated that the invention includes means for effecting step by step rotation of the card cylinder in one direction with such a single set of body weave cards passing thereover, to present successive faces of the card cylinder with successive cards of said set thereon to the needle plate of the jacquard head, for automatically thereafter 55 reversing the direction of turning movement of the cylinder to present the same cards to the needle plate in reverse order; thereafter again to reverse and to continue to reverse the direction of turning movement of the 60 cylinder, as described, until the full length of the body pattern has been woven; and thereafter and by automatic control to pass the successive and opposite end border 65 patterns cards over the card cylinder with the cylinder turning continuously in the one direction to present successive border pattern cards of the series of opposite end border 70 patterns to the needle board; and at the completion of the weaving of the successive 75 border patterns again and automatically to start the cycle of reversal of the cylinder for the next succeeding body pattern.

Mechanism is provided for controlling the direction of turning movement of the usual 80 card cylinder and is operated in timed relation to the lay, and the direction of turning movement, the duration of the reversing cycle of the cylinder and its subsequent rotatory movement for the succeeding series of end 85 border pattern cards is determinately controlled and selectively varied for different patterns and sizes of the woven units through a control which may effectively be constituted by a pattern chain of the usual type with associated mechanism cooperating with that 90 controlling the direction of turning movement of the card cylinder.

The invention, therefore, is adaptable, in principle to a wide range of woven forms 95 characterized by an intermediate body portion of similar woven units and adjoining end body portions of a pattern type requiring a series of individual pattern cards. It will be understood that in jacquard practice, each 100

card controls one "pick" or filling insertion.

The invention consists in the construction, arrangements and combinations hereinafter described and claimed and will be more clearly apparent from the following detailed specification which is to be read in conjunction with the accompanying drawings forming part thereof, and in which:

Figure 1 is a perspective view of one end of the lower portion of a Jacquard loom of standard construction having the card control mechanism of the present invention applied thereto, only such part of the standard loom construction being shown as is necessary to illustrate the application of the controlling mechanism thereto.

Figure 2 is a similar perspective view of the jacquard head overlying the loom as shown in Figure 1, showing the connection of the control of Fig. 1 with the card cylinder and showing the rotation reversing mechanism therefor operated through said control.

Figure 3 is a view in side elevation of the parts shown in Figure 1 with the chain drive for the control head omitted and the cylinder reversing cam control shown in elevation with the pattern chain control of the reversing cam shown in the position putting the border pattern cards in operation.

Figure 4 shows in elevation dual pawl arms for rotating the card cylinder positioned to turn the cylinder in a clockwise direction.

Figure 5 is a similar view with the pawl arms reversed to turn the cylinder counter-clockwise.

Figure 6 is a view in transverse section on an enlarged scale through the card control head, the section being taken approximately on the line 6—6 of Figure 3.

Figure 7 is a top plan view on an enlarged scale of the control head as shown in Figure 6.

In the accompanying drawings, I have shown the structure of my invention as applied to the cooperating elements of a Jacquard loom of standard construction, only such parts of the latter being shown in detail as are necessary to an understanding of the present invention and its operation and application.

In Figure 1, the warp beam end of the lower portion of a standard Jacquard loom is shown, with cooperating elements of the present invention applied. The usual warp beams 1 and 2 with their tension roll 3 and associated let-off mechanism are shown mounted in the lower loom frame 4 from opposite sides of which upstand bifurcated standards 5.

The upper ends of these standards, as shown in Figure 2, support horizontal beams 6 upon which the base of a standard jacquard head frame 7 rests and is supported.

The jacquard mechanism may be of any

standard construction. In the form shown the usual lifting bars or griffs 8 are carried at the top of the frame 7, which also supports the usual perforated card cylinder 9 of rectangular cross section and provided at one end with a reduced axial extension 10 of rectangular cross section, whose corner edges 11 function as ratchet teeth. The usual lifting hooks 12 engage over the upper edges of the lifting bars or griffs 8 as shown in Figure 2 and have the usual cords or wires 13 depending from their lower ends to the harness. These lifting hooks are moved into and out of position for engagement by the griff bars for lifting thereby through the usual horizontal bank of needles passing through the usual needle board and controlled by the perforations on the pattern cards 14 of the usual endless chain of pattern cards trained over the perforate face of the rectangular cylinder 9 and drawn over the cylinder which receives step by step rotatory movement, to present successive cards for movement with the cylinder to engage the needle board and move the needles and lifting hooks in accordance with the pattern perforations of the cards.

The grip bars 8 are carried between plates or frames 15 (one of which is shown in Fig. 2) which are periodically reciprocated vertically through mechanism which also effects reciprocation of cylinder 9 from and toward the needle board and the bank of needles. Reference to Fig. 1 will show that the usual cam shaft 16 actuating the loom lay is extended outwardly from the frame 4 and carries a wheel 17 at its outer end from which an eccentric crank pin 18 outstands. The lower end of a rod 19 is carried in a sleeve 20 having an offset bearing 21 in which the crank pin 18 is journaled. The rod 19 extends upwardly to the jacquard frame 7, its upper end, as shown in Figure 2 being pivotally connected to the outer end of an arm 22 extending outwardly from a rock shaft 23. A pair of oppositely extended arms 24 at opposite ends of the rock shaft (only one of which is shown) are pivotally connected at their outer ends to the lower ends of vertical bars 25 whose upper ends are journaled on studs 26 outstanding from the griff frames 15. Rotation of wheel 17 will therefore effect periodic vertical reciprocation of the griff frame and its bars 8 in timed relation to the operaton of the loom lay.

Vertical reciprocation of the griff frame is utilized to effect lateral reciprocation of the card cylinder 9 from and toward the needle board and needles. The opposite ends of the cylinder 9 are journaled in the lower ends of vertical plates or frames 27. The upper ends of the frame plates are spanned by the usual bar mounting spring arms which press the cards against the active face of the cylinder. The lower ends of the plates 27, as

shown in Figure 2, carry offset laterally-extending rods 28 guided through eyes in lugs 29 outwardly offset from the side faces of the frame 7. Between its ends each rod 28 fixedly carries an arm 30 vertically depending therefrom and having a vertically extending cam slot 31 therein. The griff frames 15 carry a vertically depending bar 32 from the lower end of which a pin 33 outstands and extends in the slot 31. From the illustrated configuration of the cam slot 31, it will be evident that upward movement of the griff frame will cause the rod 28 and cylinder 9 to be moved outwardly and away from the needle board and needles and that downward movement of the griff frame will move the bar 28 and card cylinder 9 inwardly toward the board and needles.

The loom mechanism as heretofore described forms specifically no part of the present invention and merely shows a standard form of Jacquard loom to which the present invention is applied for purposes of illustration.

In accordance with the invention, I have provided mechanisms for causing in alternation step by step axial rotary movement of the cylinder 9 in reverse directions as it is moved outwardly away from the needle board and needles through the mechanism previously described. To this end, an arm 34 is pivoted at its inner end to the upper end of the jacquard head frame 7 and extends outwardly and overlies the ratchet 10 of the card cylinder 9. At a point intermediate its ends, it is provided with a pawl tooth 35 adapted to be engaged by a corner ratchet tooth 11 of the cylinder ratchet 10 as the latter is moved outwardly from the needle board to effect an axial turning movement of the cylinder through a quarter revolution, thereby presenting a succeeding face of the rectangular cylinder to the needle board upon its subsequent return movement toward said board.

As shown in Figure 4, the pawl arm 34 functions to effect rotation of the cylinder 9 in a clockwise direction. Below the cylinder 9, the inner end of a second arm 36 is pivotally mounted on the frame 7, the arm outstanding from the frame and underlying the cylinder and being similarly provided with a pawl tooth 37 confronting the cylinder. The outer ends of the pawl arms 34 and 36 are pivotally interconnected for swinging movement in unison by a link 38. In Figure 4, the pawl tooth 35 of the upper pawl arm 34 is shown as positioned for the cooperative engagement of the pawl tooth 35 of the upper pawl arm with the cylinder to effect rotation thereof in a clockwise direction, the pawl tooth 37 of the lower pawl arm being dropped below the plane of movement of the cylinder ratchet. When the lower pawl arm 36 is moved upwardly, as shown in Figure 5, to lie in the plane of movement of the cylinder

ratchet 10, the upper pawl arm 34 is coincidentally moved through the link connection 38 out of the plane of cylinder movement. With the lower pawl arm in the position shown in Figure 5, it will be evident that outward movement of the cylinder will engage a corner edge of its ratchet 10 with the pawl tooth 37 and impart axial rotatory movement to the cylinder in a reverse or counter-clockwise direction. In accordance with the present invention, means are provided for effecting in alternation and at uniform intervals reverse swinging movement of the pawl arms 34 and 36 to impart to the card cylinder a series of step by step rotatory movements in opposite directions and of equal number. The number of such step by step movements is determined by the number of pattern cards 14, each representing one "pick" or filling insertion, which are necessary to provide a single weave unit which is successively repeated in the weaving operation as in the weaving of an intermediate body portion of fabric composed of a succession of similar weaving units as has been heretofore explained.

The described control and operation of the pair of pawl arms 34, 36, is automatically secured through the following instrumentalities. Referring to Figure 1, it will be seen that I have provided on the extended end of the lay cam shaft 16, a toothed gear 39. Above the cam shaft 16, a second shaft 40 is journaled in suitable bearings in the frame 4 and mounts externally of the frame a toothed gear 41. For Jacquard looms used in terry towel manufacture in which there are three cards and three picks to the terry weave unit of the intermediate towel body, the toothed gear 41 will bear a ratio of 6 to 1 relatively to the cam shaft 16 and its gear 39, so that the intermeshing gear 41 and its shaft 40 will be rotated once to every six revolutions of the cam shaft 16 of the lay. Within the frame 4, the shaft 40 mounts a cam 42 shown in Figure 3. The periphery of this cam is divided into two segments of equal arcuate extent, the periphery of one segment 43 being at a uniform and greater distance from the shaft 40 than the periphery of the second segment 44 with each segment representing a half revolution of shaft 40 or three picks of the loom, during which three successive pattern cards 14 are presented to the needle board. Actuating connections from the cam 42 to the pawl arms 34, 36 are provided in the form of an arm 45 pivoted at one end to a standard 5 and provided intermediate its ends with a roll 46 overlying and engaging the peripheral edge of the cam 42 and acted upon by its segments 43 and 44 in succession. To the opposite end of the arm 45 is attached a coil spring 47 through which the roll is maintained in contact with the cam periphery. To this same end of the arm 45, the lower end of a verti-

cally extending actuating rod 48 is pivotally connected. The rod 48 extends upwardly and is pivotally connected at its upper end to the outer end of a rock arm 49 fixed to one 5 end of a rock shaft 50 which traverses the loom frame below the upper end of the bifurcated standards 5 and beams 6 and is journaled in brackets 51 fixed to the standards 5 at opposite sides of the loom. The rock shaft 10 50 at the side of the loom opposite to the rock arm 49 carries a second and oppositely disposed rock arm 52. The lower end of a bent pawl operating rod 53, best seen in Figure 2, extends through an opening in the end 15 of the second rock arm 52 and is fixed to the under side of the rock arm by a nut or other suitable abutment 54. Above the rock arm, a second abutment nut 55 is fixed on the rod and a coiled spring 56 interposed between 20 the upper nut 55 and the rock arm 52 provides a resilient yielding connection between the rod 53 and the rock arm 52. The upper end of the rod 53, as shown in Figures 2, 4 and 5 is pivotally attached to the lower pawl 25 arm 36 adjacent its pivoted end. The throw of the segment 43 of cam 42 is figured to provide sufficient upward movement to the rod 48 and downward movement to the rod 53 to move the upper pawl arm 34 downwardly 30 to the cylinder ratchet cooperating position shown in Figure 4. The lower peripheral cam segment 44 is figured to permit the spring 47 to pull the arm 45 and rod 48 downwardly, with the roll 46 contacting the segment 44, a sufficient distance to in turn lift 35 the rod 53 and the lower pawl arm 36 to the position shown in Figure 5 with the upper pawl arm moved through the link connection 38 upwardly and out of the path of movement 40 of the cylinder so that it is ineffective to cause rotation of the cylinder. It will be seen, therefore, that the pawl arms 34 and 36 are alternately moved through the cam 42 and are each held in alternation in positions 45 of cooperation with the card cylinder ratchet during a period of three picks of the loom and during three reciprocations of the card cylinder 9. Consequently, with a set of three cards 14 representing a single intermediate body pattern terry weave unit, trained over three faces of the rectangular cylinder 9, the three cards will be successively presented to the needle board through one pawl, and upon reversal of the pawl, the same three 55 cards in reverse order will be successively presented and so on, so long as the cam 42 is permitted to operate. As has been previously stated, the endless chain of cards 14 will, in accordance with the present invention, embody a complete series of cards for each pick of opposite end border patterns spaced by and joined to an intervening set of three cards representing a single weave unit of the intermediate body pattern of a 60 terry towel. Obviously, the number of cards 65

and the number of step by step movements of the cylinder in reverse directions will be varied in accordance with the number of picks required for different single weave units, the ratio of the gears 41 and 39 being 70 varied to provide for the shaft 40 one revolution during double the number of picks required for the particular weave unit.

The operation of the cam 42 to provide through its actuating connections to the pawls 34, 36, repeated reversals or cycles of step by step rotatory movement of the card cylinder is controlled together with the positions of the pawl arms by means of a pattern mechanism coordinated both in timing 80 and in operation to the chain of pattern cards 14. This mechanism will be effective to condition the arm 45 for normal operation by the cam 42, and consequently to reverse the direction of rotation of the card cylinder in alternation, only during the period in the cycle of weaving in which the set of single weave unit cards 14 is trained over the cylinder 9 and during the number of weave unit cycles necessary to weave an intermediate body portion of determinate length and formed of successive repetitions of a single weave unit. At the end of this weave, the arm 45 is automatically moved to position and maintain a pawl for continuous axial rotation of the cylinder in the one direction 90 only to cause the cylinder to draw thereover and present successively to the needle board the successive individual pick cards of the end border pattern series following thereafter; also to so position the arm 45 for the continuous passage over the card cylinder of the successive cards of the end border unit preceding the single weave unit set of cards.

The shaft 40 mounting the gear 41 and 105 cam 42 is provided, outwardly of the toothed gear 41, with a sprocket gear 54 over which is trained the lower end of an endless sprocket chain 55, as best seen in Figure 1. The rock shaft 50 is supported upon the opposite 110 bifurcated standards 5 of the upper loom frame to position one end substantially above the sprocket gear 41. This end of the shaft is extended outwardly from its bearing 51 as shown most clearly in Figures 1, 6 and 7. 115 A bracket arm 56, secured at its inner end to the standard 5 below the bearing bracket 51, extends outwardly from said standard in parallel with the extended end of shaft 50 and is provided at its outer end with an upward offset 57 having a laterally extended upper end 58 to which is rigidly fixed and from which upstands a bracket arm 59 having a bearing 60 at its upper end through which the outer end of the rock shaft 50 extends and in which it is journaled. A supporting arm 61 is affixed at its lower end to the lower end of the bracket 59 and extends diagonally upwardly therefrom to position its upper end 120 above and, as shown in Figure 1, rearwardly 125

of the rock shaft 50. The upper end of this arm 61 is formed with a bore therein which receives the outer end of a fixed spindle or rod 62 extending in parallel with the rock shaft and having its inner end seating in a bore formed in the standard 5 rearwardly of the bracket 51 as is shown in Figures 6 and 7.

As shown in Figures 6 and 7, a sleeve 63 is loosely journaled on the extended end of the rock shaft 50 outwardly of the standard 5 and mounts thereon a sprocket gear 64 alining with the sprocket gear 54 on shaft 40, the upper end of the endless sprocket chain 55 being trained over the upper sprocket gear 64, to effect rotation of said gear and its sleeve 63. The sprocket gears 54 and 64 in the specifically illustrative embodiment are designed to have a ratio of 2 to 1 providing a revolution of the sprocket gear 64 to every 12 picks, representing the passage of 12 cards over the card cylinder. Obviously, this ratio may be varied since, as will be later seen, it will be merely necessary to obtain a determinate number of picks per revolution of the sleeve 63 to determine the length of the primary pattern controlling chain. The sleeve 63 also carries adjacent the sprocket 64 a double toothed sprocket 65 which may have six teeth, representing each a movement corresponding to two picks of the loom. Over this double sprocket is trained the primary timing chain 66 of the pattern control having cross bars or rungs 67 spaced to fit successive teeth of the sprocket 65, each pair of chain links having their ends connected by adjacent cross bars or rungs 67 representing, therefore, two picks. The chain 66 may for purposes of illustration have 15 links representing 30 picks of the loom to its passage over the sprocket 65.

Outwardly of the sprocket gear 65 a pair of spacer sleeves 68 are mounted on the shaft 50 serving to space from sleeve 63 a second and outer sleeve 69 which is loosely journaled on the outer end of the shaft 50. This sleeve at its respective inner and outer ends is provided with a toothed ratchet 70 and a detent wheel 71 with the notches of which a suitable spring pressed detent 72 cooperates. Intermediate its ends, the sleeve 69 is provided with a double toothed sprocket gear 73 over which is trained the upper end of a ladder type pattern chain 74 which may be termed a multiplier chain and which similarly to the double sprocket gear 65 may have a similar number of teeth, between which the cross bars or rungs 75 of the multiplier ladder chain seat, similarly to the primary chain 66.

Motion, representing a $\frac{1}{6}$ revolution or one tooth movement is imparted to the multiplier chain sprocket gear 73 from the primary pattern chain 67 for every complete passage of said chain, representing 30 picks, over its sprocket gear 65. To this end, one of the cross rungs 67 of the primary pattern chain

is provided with a bead or roll 76 extending outwardly from the cross bar and above the side links of the chain to function as a lifting surface. Cooperating with this roll is an arm 77 having a bearing 78 at its rear end 70 journaled on the rod 62 and extending forwardly over the sprocket gear 65 to overlie and aline with the lifting head or roll 76. A link 79 pivoted at its upper end to the outer end of the arm 77 has fixed to its lower end 75 a pawl 80 formed to engage beneath one of the ratchet teeth of the ratchet 70 of sleeve 69. The arm 77 is normally pressed downwardly to overlie the cross bars 67 of the primary chain for lifting engagement by its bead 76 80 by means of a coil spring 81 anchored to the arm 77 and to the underlying bracket arm 56. A tensioned spring 79a (Fig. 7) interposed between the arm 77 and the link 79 acts normally to maintain the end of the pawl pressed 85 against the under side of the ratchet wheel 70. The offset of the lifting roll or bead 76 will be figured to give the arm 77 and the pawl 80 a determinate throw which, for example, may be sufficient to rotate the sleeve 90 69 with its sprocket gear 73 through a $\frac{1}{6}$ revolution moving the pattern chain 74 there-over to the extent of one link.

The chain 74 has the function of controlling the operation of cam 42 and of the pawls 34, 95 36 and is coordinated to the chain of pattern cards 14. With each link of the pattern chain 74 representing, for example, 30 picks of the loom, one link may control the position of the pawls during 30 picks of the loom. It will be seen by referring to Figs. 1, 3 and 6, that pattern chain 74 mounts two spaced series of lifting fingers or lugs 82 upon a series of successive cross bars or rungs 75 of the pattern chain. These spaced series of lugs 100 105 will present continuous lifting surfaces representing the number of picks in opposite end border patterns with the long series of plain cross bars 75a (Fig. 1), intervening between the very substantially spaced ends of the two 110 series 82 representing the picks for an intermediate body weave portion in which a single weave unit is repeated. The short series of plain cross links, as 75b between the closely adjacent ends of the series of lugs 82, will represent, for example, end selvage strips separating successively woven complete pattern units and providing hems and a cut line there-between as is customary in the weaving of towels. The lugs 82 are intended to operate 115 certain connections to disconnect the pawl actuating arm 45 from control of the cam 42 and coincidently to control and maintain a pawl, as for example, the pawl 34, 35 for cooperation with the ratchet 10 of the card cylinder 120 to provide a continuous step by step rotatory movement of the card cylinder in one direction only—i. e., clockwise, during the period each series of successive lugs 82 are passing over a certain portion of the sprocket gear 73. 125 130

Control of the cam 42 and pawls 34, 36 through the pattern chain 74 is secured through a U-shaped bracket member 83 and journaled at its rear ends upon the rod 62 and having one side arm overlying the cross bars or rungs 75 of the pattern chain and flattened as at 84, Figures 6 and 7, for engagement of its under side with the cross bars 75 or with the lugs 82 as they pass thereunder, in the movement of the chain upwardly over the sprocket gear 73. From the outer end of the U-shaped bracket 83 a rod 85 extends downwardly and is anchored to the outwardly offset end of a pin 86 fixedly secured to and outstanding from the upright end of an L-shaped pivoted arm 86 pivoted at its opposite end as at 87, Fig. 3, on the frame 4 adjacent the shaft 40 and cam 42. The upper end 88 of this L-shaped arm underlies the pawl actuating arm 45 adjacent its outer swinging end. The weight of the hinged U-shaped bracket 83 is normally sufficient to hold it down to engage its flat portion 84 with the cross bar 74 of the pattern chain. When there are no lugs present on that portion of the chain passing over the top of the sprocket gear 73 and underlying the flat portion 84, the bracket and wire 85 will be lowered to swing the arm 86 downwardly to the dotted line position shown in Figure 3 in which position the cam 42 is permitted to raise and lower the pawl actuating arm 45 in alternation, causing the periodic reversal or rotary movement of the card cylinder as heretofore described. When, in the travel of the pattern chain over the top of the sprocket gear 73, the initial one of a succession of lugs 82 passes under the flat bar portion 84 of the swinging bracket 83, the latter will be lifted, pulling upwardly on the wire 85 and moving the end 88 of the disengaging arm 86 upwardly to lift the arm 45 to a point representing its maximum lifted position through the cam 42 and to maintain the arm 45 so lifted during the progressive travel of the entire series of lugs 82 beneath the flat abutment portion 84 of the bracket. This upwardly moved position of the arm 45 will move and maintain the pawl arm 34 and pawl 35 in the position of Figure 4 so that a continuous step by step rotatory movement in a forward or clockwise direction only will be imparted to the card cylinder during the entire period that the series of lugs 82 is maintaining the swinging bracket 83 in upraised position, this period representing the weaving of an entire end body pattern portion during which the entire series of successive individual pick end border pattern cards 14 are successively drawn over the card cylinder 9 and presented successively to the needle board. Since the pattern chain is driven through the lay cam shaft 16 and intermediate gearing has a definite ratio thereto, the pattern chain 74

has determinate pick value (or number of picks of the loom which each link represents) and determinate control of the woven pattern can be secured therethrough. Ordinarily in continuous weaving in Jacquard looms, an end selavage space is woven between the abutting end patterns of successive woven units providing a line of cut and separation therebetween. In this event, the chain of cards 14 will include two complete series of end border pattern cards with the single weave unit set of the intermediate body pattern units interposed therebetween, the other ends of the series of opposite end border pattern cards having in this case interposed therebetween the number of pattern cards requisite to the weaving of this end selavage strip. The pattern chain 74 under such conditions would have one or more cross bars (75b) without lugs 82 between adjacent ends of the series of border controlling lugs 82 with the opposite ends of these series of lugs spaced between the long length of pattern chain with plain cross bars 75a representing the extent or number of picks 90 of the intermediate body pattern portion.

Obviously, the pattern chain is initially positioned on the sprocket gear 73 to coordinate its active link, or that engaging the flat portion 84 of the bracket 83 with the particular pattern card or series of pattern cards trained over the card cylinder 9 so that the movement of these cards over the cylinder and the movement of the pattern chain is coordinated, the unit length of the card chain 100 and the pick value of the pattern chain corresponding. By utilizing a multiplier chain as a pattern chain the length of the chain is very substantially reduced. The uniform pick value of each link may, of course, be increased or decreased by variance of the gear ratio transmitting motion to the primary chain 67 and by increasing the length of the primary chain.

From the foregoing, it will be evident that I have provided mechanism enabling the repeated use of a single weave unit series of cards to weave into the fabric pattern a consecutive series of weave units for a body pattern composed of a succession of similar weave units and have also provided mechanism giving positive and automatic control of the weaving operation and of continuity of card cylinder reversal. Not only do these means result in the saving of a relatively large, and as compared with previous practice, enormous, number of pattern cards but accomplishes this result without sacrifice of absolute control of weaving and is flexible and adaptable to weave units of varying numbers of picks and to varying patterns of weave. While the described specific form of the invention represents a preferred embodiment thereof, which in practice has proven entirely satisfactory, the illustrated form is 130

intended as descriptive of the invention rather than restrictive thereof and is subject to modification and variation in adapting the invention to different conditions of manufacture and use.

What I claim, therefore, and desire to secure by Letters Patent is:

1. In a Jacquard loom, a needle board, a continuous chain of pattern cards comprising a complete series of opposite end border pattern cards and an interposed single weave unit set of intermediate body pattern cards, a card cylinder over which said chain of cards is trained and which is movable toward and from the needle board and is rotatable step by step to present successive cards to said needle board, means for reciprocating said cylinder toward and from the needle board, means selectively positioned to engage and impart step by step rotatory movement to said cylinder in reverse directions during the reciprocations thereof, and controlling mechanism therefor, controlling pattern mechanism coordinated with said card chain and including a sprocket gear driven in timed relation to the loom lay, a chain trained thereover and movable thereby, a second and independently rotatable sprocket gear and a multiplier pattern chain trained thereover, means for imparting step by step movement of the second sprocket gear and its multiplier chain in determinate ratio to the movement of the primary chain and means carried by said multiplier pattern chain and positioned thereon in coordination with said card chain and operative at coordinated points in the weaving cycle, for positioning said cylinder rotating means to effect continuous step by step rotation of the cylinder in one direction to draw a series of end border pattern cards thereover and present successive cards of said series to the needle board in continuity to the extent of said series of border cards and until said single weave unit set of cards passes to said cylinder, for then automatically positioning said cylinder rotating means to effect step by step rotatory movement of the cylinder in alternately reverse directions successively to present to the needle board, by reversal, successive cards of the body weave unit set in repetition for the duration of the full intermediate body pattern weave, and at the end of said body weave, and operative automatically to position said cylinder rotating means to resume continued step by step rotation of the cylinder in the first named direction to draw the cards of the next succeeding border pattern series thereover for successive presentation of the needle board.
2. In a Jacquard loom embodying a needle board, a continuous chain of pattern cards comprising complete series of end border pattern cards and an interposed set of single weave unit intermediate body pattern cards, and a card cylinder over which said card chain is trained and which is mounted for bodily reciprocating movement toward and from the needle board and for rotatory movement about its axis to draw successive cards of said chain of cards thereover for successive presentation to the needle board, a ratchet on said cylinder, a pair of coacting pawls connected for conjoint movement to place alternate pawls in cooperative relation to said cylinder ratchet and effect step by step rotation of said cylinder in reverse directions when said cylinder is reciprocated to engage its ratchet with a pawl, mechanism operating in timed relation to the lay for continuously reciprocating said cylinder, means operated in timed relation to the lay and operatively connected to said pawls and constructed alternately to move said pawls to cooperate with the cylinder ratchet and reverse the direction of rotation imparted to the cylinder in successive cycles representing single weave units of said intermediate body pattern, and a controlling pattern mechanism coordinated with said card chain and including a sprocket gear driven in timed relation and determinate ratio to the loom lay, a pattern chain trained thereover and moved thereby, and means carried by said chain operative at the termination of said body weave to position said pawls to give continued step by step rotatory movement to the cylinder in the one direction only to pass successive cards of an end border series of cards thereover in continuity for the duration of the complete end border pattern weave and to the extent of said series of cards.
3. In a Jacquard loom embodying a needle board, a continuous chain of pattern cards comprising complete series of end border pattern cards and an interposed set of single weave unit intermediate body pattern cards, and a card cylinder over which said card chain is trained and which is mounted for bodily reciprocating movement toward and from the needle board and for rotatory movement about its axis to draw successive cards of said chain of cards thereover for successive presentation to the needle board, a ratchet on said cylinder, a pair of coacting pawls connected for conjoint movement to place alternate pawls in cooperative relation to said cylinder ratchet and effect step by step rotation of said cylinder in reverse directions when said cylinder is reciprocated to engage its ratchet with a pawl, mechanism operating in timed relation to the lay for continuously reciprocating said cylinder, a cam rotated in timed relation to the lay operatively connected with said pawls and constructed alternately to move said pawls to cooperate successively with the cylinder ratchet to impart to the cylinder step by step rotation in reverse directions and in successive cycles representing single weave units of said in-

termediate body pattern, a controlling pattern mechanism coordinated with said card chain and including a sprocket gear driven in timed relation to the loom lay, a chain trained thereover and moved thereby, a second and independently rotatable sprocket gear and a multiplier pattern chain trained thereover, means for imparting step by step movement of the second sprocket gear and its multiplier chain in determinate ratio to the movement of the primary chain and means carried by said multiplier pattern chain and operative to permit operation of said cam to cause alternate reversal of rotation of the cylinder with the single weave unit set of cards thereon in continuity for the duration of the entire intermediate body weave and to inoperatively condition the cam for alternate reversal at the end of said body weave and to position said pawls for continued step by step rotatory movement of the cylinder in one direction only with an end border pattern series of cards passing continuously thereover for the duration of the complete end body pattern weave and to the extent of the series of end body pattern cards.

4. In a Jacquard loom, a needle board, a card cylinder bodily reciprocable toward and from the board and axially rotatable to draw thereover and present successive cards of said chain to said board, a chain of cards trained over said cylinder including a single set of cards representing a single weave unit continuously and determinately repeated in the pattern to be woven, a ratchet carried by said cylinder, a pair of opposed pawls movable alternately to cooperate with said ratchet during reciprocation of the cylinder to effect step by step axial rotation of the cylinder in reverse directions, a cam rotating in timed relation to the loom lay, actuating connections from said cam to said pawls, said cam being formed and normally operating alternately to move said pawls to positions to effect reversal of the direction of cylinder rotation at step by step intervals corresponding to the number of cards forming said single weave unit set, disconnecting means operable to move and hold said actuating connections from normal cooperative relation to said cam and coincidentally to position and hold one of said pawls to effect continued rotatory movement of the cylinder in one certain direction, and a controlling pattern mechanism coordinated with said card chain and including a sprocket gear driven in timed relation and determinate ratio to the loom lay, a pattern chain trained thereover and moved thereby, and means carried by said chain positioned thereon in coordination with said card chain and operative at coordinated points in the weaving cycle to actuate said cam disconnecting means to discontinue reversal of cylinder rotation through said cam and to position and maintain one of said pawls in position for

repeated step by step rotation of the cylinder in one direction.

5. In a Jacquard loom, a needle board, a card cylinder bodily reciprocable toward and from the board and axially rotatable to draw thereover and present successive cards of said chain to said board, a chain of cards trained over said cylinder including a single set of cards representing a single weave unit continuously and determinately repeated in the pattern to be woven, a ratchet carried by said cylinder, a pair of opposed pawls movable alternately to cooperate with said ratchet during reciprocation of the cylinder to effect step by step axial rotation of the cylinder in reverse directions, a cam rotating in timed relation to the loom lay, actuating connections from said cam to said pawls, said cam being formed and normally operating alternately to move said pawls to positions to effect reversal of the direction of cylinder rotation at step by step intervals corresponding to the number of cards forming said single weave unit set, disconnecting means operable to move and hold said actuating connections from normal cooperative relation to said cam and coincidentally to position and hold one of said pawls to effect continued rotatory movement of the cylinder in one certain direction, and a controlling pattern mechanism coordinated with said card chain and including a sprocket gear driven in timed relation to the loom lay, a chain trained thereover and moved thereby, a second and independently rotatable sprocket gear and a multiplier pattern chain trained thereover, means for imparting step by step movement of the second sprocket gear and its multiplier chain in determinate ratio to the movement of the primary chain, and means carried by said multiplier pattern chain and positioned thereon in coordination with said card chain and operative at coordinated points in the weaving cycle to actuate said disconnecting means to discontinue reversal of cylinder rotation through said cam and to position and maintain one of said pawls in position for repeated step by step rotation of the cylinder in one certain direction.

6. In a Jacquard loom, a needle board, a card cylinder bodily reciprocable toward and from the board and axially rotatable to draw thereover and present successive cards of said chain to said board, a chain of cards trained over said cylinder including a single set of cards representing a single weave unit continuously and determinately repeated in the pattern to be woven, a ratchet carried by said cylinder, a pair of opposed pawls movable alternately to cooperate with said ratchet during reciprocation of the cylinder to effect step by step axial rotation of the cylinder in reverse directions, a cam rotating in timed relation to the loom lay, actuating connec-

tions from said cam to said pawls, said cam being formed and normally operating alternately to move said pawls to positions to effect reversal of the direction of cylinder rotation at step by step intervals corresponding to the number of cards forming said single weave unit set and disconnecting means operable to move and hold said actuating connections from normal cooperative relation to said cam and coincidently to position and hold one of said pawls to effect continued rotatory movement of the cylinder in one certain direction.

7. The combination with a Jacquard loom employing a card cylinder, a card chain trained thereover, a pair of pawls alternately operable to rotate said cylinder in reverse directions and an operating mechanism for said pawls; of means for disconnecting said pawls from their operating means, a controlling pattern mechanism coordinated with said card chain and including a sprocket gear driven in timed relation to the loom lay, a chain trained thereover and moved thereby, a second and independently rotatable sprocket gear and a multiplier pattern chain trained thereover, means for imparting step by step movement of the second sprocket gear and its multiplier chain in determinate ratio to the movement of the primary chain, and means carried by said multiplier pattern chain and positioned thereon in coordination with said card chain and operative at coordinated points in the weaving cycle to actuate said disconnecting means and to position and maintain one of said pawls in position for repeated step by step rotation of the cylinder in one certain direction.

ERNEST HALL.
